DEWAXING OIL

Donald E. Carr, Long Beach, and Maner L. Wade, Naples, Calif., assignors to Union Oil Company of California, Los Angeles, Calif., a corporation of California

Application August 26, 1935, Serial No. 37,940

18 Claims. (Cl. 196—18)

The present invention relates to the art of separating wax from wax-bearing oil, and more particularly the invention pertains to a method in which certain materials are added to the wax-bearing oil to condition the latter so that the wax may be more readily separated from the oil. The invention also relates to a process for the production of materials which when added to a wax bearing oil, condition the latter so that the wax may be more readily removed therefrom. The invention is also applicable for the separation of oil from wax such as slack wax, wax cakes, etc.

Many oils contain relatively large quantities of wax which impart a high pour point to the oil and thereby render these oils unsuitable for use as they are solid and will not flow at ordinary temperatures. In order to render these oils fluid at ordinary temperatures, it is necessary to remove the wax present. This is usually accomplished by adding a suitable diluent to the wax-bearing oil, chilling the diluted oil to a temperature sufficiently low to precipitate or solidify the wax and then separating the precipitated wax from the diluted oil by settling, filtering or centrifuging.

We have discovered that wax present in oils may be more readily separated by mixing the wax-bearing oil with certain materials which render the wax more readily separable from the oil. Hereinafter, the materials which we employ to condition the wax present in wax-bearing oils in order that the wax may be more readily separated from the oil will be referred to as "wax modifiers" or "wax separation aids".

In general, the wax separation aids which we employ to condition the wax-bearing oil to render the wax more readily separable, comprise oxidized paraffinic substances. Such oxidized paraffinic substances include oxidized waxes, such as scale wax, slack wax, chemically refined water white high or low melting point waxes, oxidized petrodatum, oxidized ceresin, oxidized oils containing large or small quantities of wax and/or petrodatum, oxidized raffinates produced by solvent extraction of oils and which may be substantially free from wax or may contain large or small quantities of wax, oxidized petroleum distillates either substantially free from wax or containing large or small quantities of wax and oxidized petroleum residues either substantially free from wax or containing large or small quantities of wax. We have discovered that the foregoing oxidized wax separation aids are quite active in conditioning the oil to be dewaxed so that the wax may be more readily separated from the

oil. The reason for this phenomenon is not definitely known but we do know that when small amounts of the oxidized material is added to the oil to be dewaxed, an improvement is obtained with respect to the yield of dewaxed oil, filter rate or rate of wax separation and melting point of the separated wax. When the same amount of the materials prior to their oxidation are added to wax-containing oils, the improvement obtained is not sufficiently increased with respect to yield, filter rate and quality of the wax separated over the unaided dewaxing process as to warrant their use in commercial dewaxing processes.

In general, the oxidized wax separation aids may be produced by subjecting the unoxidized waxes or oils to the action of an oxygen-containing gas such as air, oxygen or ozone, preferably at an elevated temperature. Certain types of materials among those mentioned above require no treatment, chemical or otherwise, previous to oxidation to produce the active wax separation aid. However, it is beneficial in the case of certain stocks, such as crude slack waxes, to prepare them for more effective oxidation by a preliminary removal of undesirable impurities, such as resins, reactive oil fractions, etc.

Preferably, when producing the wax separation aid from slack waxes or waxes containing considerable quantities of oil, the crude wax is first deoiled to a low oil content. This may be accomplished by dissolving the wax in a suitable solvent such as propane, then chilling the solution to reprecipitate the wax and filtering the mixture. If desired, the crude wax may be washed with cold propane or other suitable cold solvent to separate the oil from the crude material. Also, if desired, the wax may be sweated to remove the contained oil in accordance with known methods.

The crude deoiled wax may be subsequently acid treated. This is for the purpose of removing asphalt and other easily oxidized materials which seem to be reactive with oxygen or other oxygen-containing gas in preference to the paraffinic components. In other words, we have found that when wax is contaminated with large quantities of low A. P. I. gravity materials, these latter materials prevent the proper course of oxidation to such an extent that it is not feasible to produce a dewaxing aid from such stocks. The acid treatment also reduces the ratio of oil to wax in the slack wax and leaves only the more stable oils in the slack wax. When the wax has been sufficiently deoiled, the acid treatment may not be necessary providing no considerable pro-

portions of asphalt or resinous materials are present in the wax. If desired, the crude slack wax may be deoiled and deresinated by spraying the wax at a temperature above its melting point 5 into a bath of liquid propane maintained at -40° F. This causes the wax to solidify in discrete particles and sufficient time is allowed for the propane to leach the oil from the solidified particles. The recovered wax may then be heated to 10 above its melting point and allowed to stand. By decanting the wax while fluid, it will be found that the asphalt and resinous materials have settled to the bottom of the vessel.

The acid treatment will, of course, vary with 15 the type of crude wax treated but will usually be at about 10 to 25° F. above the melting point of the wax. The acid treatment should be carried out in stages employing the proper amount of acid, such as 98% sulfuric acid, consisting with 20 good settling of sludge produced by the reaction with the acid. The sludge produced by the first dump of acid may be quite viscous, especially if not withdrawn promptly. Therefore, care should be taken to obtain sufficient agitation and settling 25 without permitting the sludge to have time to thicken excessively. After the last of the sludge is separated from the wax, the latter is heated to a temperature between 140 to 200° F. which is sufficient to reduce the viscosity of the wax for 30 alkali treatment and water washing. The water washing between the acid and alkali treatments may be started immediately after withdrawing the sludge and may be continued as the temperature is raised. The water washing need not be extremely 35 thorough to remove soaps and excess caustic after neutralization. In fact, the presence of a small amount of the sodium compounds have been found to be beneficial in the subsequent oxidation step.

40 The wax, either chemically treated and/or deoiled as the case may be, is then subjected to oxidation. The conditions and degree of oxidation will vary with the type and oil content of the wax. In general, the more completely deoiled and refined waxes will tolerate a higher degree of oxidation than waxes which contain substantial quantities of oil. The oxidation consists in heating the wax to a temperature of between 350 and 500° F. and introducing air, oxygen or ozone into 45 the charge until a sufficient oxidation has taken place to render the material active as a wax separation aid and yet retain its compatibility with the oil to be dewaxed. During the oxidation, there is a period of induction during which little 50 or nothing appears to be happening. This may last up to twelve hours or longer, depending upon the degree of contact of the air with the charge and the temperature of oxidation. After this period, the oxidation reactions move fairly rapidly, 55 and it is desirable to stop the oxidation before the charge reaches a stage where it is only sparingly compatible with the waxy oils to be dewaxed.

60 The degree of oxidation may be determined approximately by measuring the acid and saponification numbers of the oxidized charge. However, these values are not entirely indicative of the wax separation aid effectiveness of the charge since the optimum amount may vary with different types of charging stocks. For example, 65 with an acid treated slack wax, whereas the oxidation should not be carried to an acid number above 5 and a saponification number above 30, in the case of substantially deoiled and refined waxes, the oxidation may be continued until the 70 charge has an acid number between 15 and 100

75 and a saponification number between 80 and 300. The acid and saponification numbers are determined according to the methods outlined by the American Society of Testing Materials, methods D-188-27T and D-94-28, respectively.

5 Also, indicative of the degree of oxidation of the charge, are the increases in specific gravity, viscosity and melting point. In general, the oxidation should not be carried to such a point that the viscosity and melting point are excessively high, 10 rendering the subsequent handling of the oxidized material difficult.

We have also found that the substances to be oxidized may be efficiently oxidized to produce wax separation aids by the use of hydrogen peroxide. The oxidation with hydrogen peroxide may be carried out advantageously in the presence of a stream of air or oxygen while maintaining the charge at an elevated temperature. The hydrogen peroxide may be added continuously 15 to the charge as a liquid solution while maintaining the charge at an elevated temperature. Preferably, air is simultaneously introduced into the heated charge while adding the hydrogen peroxide. If desired, air may be passed through 20 a separate vessel containing hydrogen peroxide and the activated air or oxygen thence passed into the heated charge. The temperature to which the charge is heated will depend upon the nature of the particular charge to be oxidized. Paraffins, 25 for example, may be satisfactorily oxidized at a temperature between 350 to 400° F. The use of paraffins oxidized with hydrogen peroxide is advantageous with respect to the color of the oxidized wax obtained. Hydrogen peroxide, in addition to being an effective oxidizing agent exerts 30 a bleaching action on the wax producing a very pale wax which does not impair the color of the dewaxed oil when employed as a wax separation aid.

40 The oxidation reaction with air, oxygen or ozone or with hydrogen peroxide may be aided when the oxidation reaction is carried out in the presence of catalysts. Catalysts which may be employed for this purpose are metal chlorides, 45 such as the chlorides of iron, zinc, tin, aluminum, metal soaps such as the naphthenates (oleates, stearates, ricinoleates, palmitates) of sodium, copper, magnesium, aluminum cobalt and iron.

In carrying out our invention, a small amount, 50 i. e. 0.3 to 1% by volume of the wax separation aid is mixed or dissolved in the wax-bearing oil after which the mixture is chilled to a sufficiently low temperature to precipitate or solidify the wax in the oil. The solidified wax may then be separated from the chilled mixture by settling, centrifuging or filtering. The added wax separation aid will be precipitated and removed with the wax. If desired, the wax separation aid may be first mixed or dissolved at an elevated temperature such as, for example, about 350° F. in a 55 small quantity of the waxy distillates to be dewaxed. The concentrated solution may then be added to the waxy distillates in such an amount so as to incorporate the desired amount of the 60 wax separation aid.

Better results will be obtained when adding 65 as wax separation aid such oxidized waxes as are produced from the same types of oil as the oil to be dewaxed. Thus, if it is desired to dewax an S. A. E. 20 waxy stock, it is preferable to employ an oxidized wax which was recovered from an S. A. E. 20 waxy stock; if it is desired to dewax an S. A. E. 50 oil, superior results will be obtained 70 by employing an oxidized S. A. E. 50 wax. Like- 75

wise, when dewaxing S. A. E. 70 stocks, an oxidized S. A. E. 70 wax should be employed. The reason for this phenomenon is not definitely understood, but we have found that by employing 5 the oxidized wax from the same type oil to be dewaxed, better results will be obtained with respect to the yield of oil, filter rate and quality of the wax.

It is preferable to employ as a wax separation 10 aid, the wax which is removed from the same oil and which is oxidized. This means that the wax removed from the oil will contain a small amount of oxidized wax which was added to the oil to be dewaxed. This mixture is then oxidized and employed 15 for aiding in the wax separation of further quantities of the same oil. By this procedure, better results will be obtained due to the fact that the oxidized wax employed as a wax separation aid in dewaxing oils will produce a wax which 20 will have a lower oil content and thus the separated wax will oxidize into a wax separation aid having superior wax modifying properties than one containing large amounts of oil.

It will be observed that when referring to an 25 S. A. E. 20, 50, 70, etc., waxy stock, we mean that the waxy distillate will yield upon complete refining, such as after separating the wax and low grade lubricating oil fraction such as those which 30 are soluble in selective solvents such as liquid sulfur dioxide and the like, an oil corresponding to the range of viscosities covered in the S. A. E. designation is employed. By an S. A. E. 20, 50, 35 70, etc., wax, we mean a wax which is separated from the waxy distillate having the particular S. A. E. designation after dewaxing and selective solvent extraction.

In many cases, it is desirable to dilute the mixture of wax-bearing oil and wax separation aid with a suitable diluent prior to the chilling step 40 in order to render the oil fluent at the dewaxing temperature. As diluents for the wax-bearing oil, we may employ liquefied normally gaseous hydrocarbons such as ethane, ethylene, propane, propylene, butane, butylene or mixtures thereof, 45 light hydrocarbons such as pentane, hexane, heptane, octane, nonane, or hydrocarbon fractions such as naphtha, gasoline, kerosene or gas oil. We may also employ such diluents as acetone, mixtures of acetone and benzol, ethyl alcohol, 50 propyl alcohol, butyl alcohol, methyl ethyl ketone, diethyl ketone, methylpropyl ketone, ethyl-propyl ketone, cyclohexanone, normally gaseous and normally liquid ethers, methyl chloride, dichlorethylene or trichlorethylene or mixtures of 55 these materials with the aforementioned hydrocarbons.

The use of a liquefied normally gaseous diluent such as liquid propane is preferred since in addition to having the property of retaining less wax 60 in solution at low temperatures, it may be employed to produce the necessary degree of refrigeration to precipitate the wax from the solution by vaporizing a portion of the liquefied normally gaseous material from the diluent oil under 65 reduced pressure.

While the foregoing is specifically directed to the addition of extraneous wax separation aids to oils to be dewaxed, we have also discovered that the dewaxing characteristics of oils may be improved by oxidizing the stock prior to chilling and dewaxing. Thus, by subjecting the oil to be dewaxed to the action of air, oxygen or ozone or even hydrogen peroxide, the wax separation aids 70 may be produced in situ. While this procedure 75 is not to be preferred over the previous method of

adding a small amount of the oxidized wax separation aid, since it involves the necessity of oxidizing the entire charge of oil to be dewaxed, it is nevertheless within the scope of our invention.

It is thus an object of our invention to improve 5 dewaxing characteristics of wax-containing oils by adding a small quantity of an oxidized wax to the oil to be dewaxed.

A further object of our invention resides in the use of oxidized petroleum fractions which were 10 either substantially free from wax or contain large or small quantities of wax prior to their oxidation, such materials being added in sufficient quantities of wax-containing oils to improve 15 their dewaxing characteristics. 15

Another object of our invention resides in a process for separating wax from oils by first oxidizing the wax-containing oil and then separating the wax from the oxidized oil.

It is a further object of our invention to accomplish 20 oxidation by subjecting the material to be employed as a wax separation aid for the oil to be dewaxed to the action of an oxygen-containing gas such as air, oxygen or ozone at an elevated temperature. It is also an object of 25 our invention to effect the oxidation by means of such liquids as hydrogen peroxide, preferably by agitating the material to be oxidized with air. It is a further object of our invention to effect the oxidation in the presence of catalysts. It is 30 a further object of our invention to separate as much of the oil contained in slack waxes as is possible prior to oxidation to produce the wax separation aid.

A further object of our invention resides in 35 dissolving the wax-bearing oil to be dewaxed and oxidized wax separation aid or the oxidized oil to be dewaxed in a suitable diluent, chilling the mixture and separating the precipitated wax from the diluted oil. The use of a liquefied normally 40 gaseous hydrocarbon such as propane is preferred because the necessary degree of refrigeration may be accomplished by vaporizing a portion of the diluent under reduced pressure.

It is a further object of our invention to employ 45 as a wax separation aid, an oxidized wax produced from oils of the same character as the oil to be dewaxed.

Many specific objects, features and advantages 50 of our invention will become apparent to those skilled in the art as the description of our invention proceeds in connection with specific examples given below which are not considered as limiting our invention but merely illustrative of methods of carrying it out. 55

The drawing represents a diagrammatic system for carrying out our invention. According to the drawing, a heated waxy oil or wax-oil mixture is taken from tank 1 via line 2 controlled by valve 3 and pump 4 and is commingled in line 5 with a small amount of oxidized wax taken from tank 6 via line 7 controlled by valve 8. The mixture then passes through a mixer 9 where the oxidized wax is completely mixed with the waxy oil. This mixture is then diluted in line 11 and 60 mixer 16 with a sufficient amount of a suitable diluent taken from tank 12 via line 14 controlled by valve 15. The diluted mixture then passes into a chiller 17 where the mixture is chilled to a wax precipitation temperature and is passed 65 via line 18 to a suitable wax separator 19 such as a filter or settling chamber, the mixture of wax and oxidized wax being removed via line 20. The dewaxed oil and diluent is removed via line 70 21 and passes to an evaporator 22 where the 75

diluent is separated from the dewaxed oil, the diluent vapors passing via line 23 to suitable condensing means (not shown). The dewaxed oil is withdrawn via line 24.

5 *Examples of use of oxidized scale wax*

A 6 gallon charge of crude scale wax having a melting point of 123° F. was heated in a still to a temperature of 450° F. after which air 10 was introduced into the charge, first at a rate of 0.27 cu. ft. per minute for approximately 72 hours and then at a rate of 0.40 cu. ft. per minute. The oxidized wax upon completion of 15 the oxidation for 94 hours had an acid number of 7, a saponification number of 65, a melting point of over 300° F. and a specific gravity at 60° of 0.865.

The oxidized crude scale wax was mixed in a closed vessel with an S. A. E. 20 waxy lubricating oil distillate obtained by the vacuum distillation of a Santa Fe springs crude oil. The oxidized crude scale wax was mixed with the waxy distillate at a temperature of about 300° F. and in an amount as to incorporate approximately 0.3% by volume into the waxy distillate. The resulting mixture was then mixed with approximately 4.5 volumes of liquid propane under superatmospheric pressure. The temperature of the resulting mixture was about 130° F. and the 30 pressure was about 250 lbs. per sq. in. The mixture of waxy lubricating oil, propane and wax modifier was then chilled externally at a rate of approximately 3° F. per minute to approximately -40° F., the refrigeration being accomplished by vaporizing under gradually reduced pressure, a portion of propane in a jacket surrounding the chilling vessel. The chilled slurry of propane, lubricating oil, solidified wax and wax modifier was filtered under a pressure of 40 about 25 lbs. per sq. in. to effect the separation of the precipitated wax and wax modifier from the propane solution of the lubricating oil. The filter rate was 4.9 gallons per square foot of filter surface per hour based on the propane free oil. 45 It will be observed that all determinations of filter rates discussed herein are based on the dewaxed oil after separating the propane therefrom. The filtrate was then distilled to remove the propane. Approximately 81.7% by volume 50 of dewaxed oil was recovered having a pour point of -5° F. The separated wax had a melting point of 130° F. as determined by the Galician method.

In another run employing 1% of the above 55 type wax modifier oxidized 72 hours at 450° F. on another portion of the same oil which was dewaxed under the same conditions as above, except that a propane to oil ratio of 2 to 1 was employed, a filter rate of approximately 3.0 60 gal./sq. ft./hr. was obtained. Approximately, 80.8% by volume of oil was recovered having a pour point of -10° F. The separated wax had a melting point of 128° F.

The results obtained in the foregoing examples 65 indicated that this type of wax modifier is quite active in dewaxing oils when compared with a blank run wherein no wax modifier is employed. The blank run on the same oil and using same amount of propane and carried out under 70 the same dewaxing conditions as above, showed that only 65.7% by volume of oil was obtained having a pour point of -5° F. The wax separated from the oil had a melting point of only 115° F.

75 A refined scale wax having a melting point of

123° F., that is, a crude scale wax which was recovered from an S. A. E. 10 waxy distillate and which was deoiled and treated with sulfuric acid, neutralized with alkali and clay treated, was oxidized with pure oxygen at a temperature of 450° F. for approximately 22 hours. The oxidized wax had an acid number of 10.4, and a saponification number of 106.3.

Propane dewaxing runs on an S. A. E. 20 waxy vacuum distillate according to the procedure described in the first example, employing 0.20, 0.50 and 1.00% by weight of the oxidized wax modifier showed filter rates of 8.3, 8.0 and 7.5 gal./sq. ft./hour, respectively, based on the viscous oil, yields of dewaxed oil of 81.9, 85.0 and 85.9% by 15 volume, respectively, each having a pour point of -5° F. and separated waxes of 128, 131 and 131° F. melting point, respectively.

In another run, 1% by weight of the above oxidized refined scale wax was employed as a 20 wax separation aid for dewaxing an S. A. E. 50 waxy distillate according to the propane dewaxing method described in the first example, employing, however, two volumes of propane to one of the oil. A yield of 80.5% by volume of dewaxed oil was obtained having a pour point of -5° F. at a filter rate of 3.1 gal./sq. ft./hr. The melting point of the wax separated was 140° F. according to the Ubbelohde method.

Examples of use of oxidized S. A. E. 50 wax 30

A slack wax obtained by dewaxing an S. A. E. 50 waxy distillate which was produced by the vacuum distillation of a Santa Fe Springs crude oil was first deoiled by dissolving it in propane 35 and chilling the solution to reprecipitate the wax and recovering the precipitated wax by filtration. The deoiled wax was subsequently given a heavy acid treatment and then wet neutralized preparatory to oxidation with pure oxygen. The acid 40 treatment was carried out with 20 lbs. per barrel of 103% sulfuric acid at a temperature of 210° F. It was neutralized with 35% of 5% caustic soda solution at 210° F. and water washed with three 45 dumps of 100 volume percent each of water. The treated wax had a melting point (Galician) of 150° F. This material was then oxidized at a temperature of 450° F. with pure oxygen for approximately 10 hours. The finished product had an acid number of 16.0 and a saponification 50 number of 82.2.

When an S. A. E. 20 vacuum distillate was dewaxed in the presence of 1% of this material according to the propane dewaxing method outlined in the first example, a yield of 83.0% by 55 volume of -10° F. pour point oil was obtained and a wax was recovered having a melting point (Galician) of 130° F. The filter rate was approximately 6.6 gal./sq. ft./hr.

It is significant to note that when the un- 60 oxidized wax was employed as a dewaxing aid in dewaxing of the same character oil, according to the same procedure, the yield of oil obtained was only 69.2% by volume. This does not represent sufficient improvement over the blank run described in the first example to indicate appreciable modifier action on the part of the unoxidized S. A. E. 50 wax.

In another run, crude slack wax was obtained 65 from a Santa Fe Springs S. A. E. 50 waxy distillate having a melting point of 131° F. as determined by the Ubbelohde method and an oil content of 50.3% as determined by the acetone-benzene method. The latter method consists in extracting the oily wax with a mixture of 65% by vol- 75

ume acetone and 35% benzene in an amount of 50 ml. of solvent to 1 gram of wax and separating the wax at -10° F. by filtration. The amount of oil dissolved by the acetone-benzene mixture 5 represents the amount of oil originally present in the wax. The aforementioned slack wax was acid treated first with 30 lbs. and then with 45 lbs. of 98% sulfuric acid per barrel of wax at a temperature of 145 to 165° F. The acid treated 10 wax was then washed at 175 to 200° F. with 20% of 2.5° Baumé caustic soda, followed by water washing and then blowing bright with air at 240° F. A neutral wax was recovered having an oil content of 35.7% and a melting point (Ubbelohde) of 138° F. This material was then 15 oxidized by blowing it with air at a temperature of 450 to 500° F. for about 26 hours, samples being taken at the end of 16, 24 and 26 hours of blowing with air.

20 Test runs in dewaxing an S. A. E. 20 vacuum distillate obtained from Santa Fe Springs crude oil were made employing 1% of each of the oxidized samples. Dewaxing was carried out in accordance with the procedure outlined in the 25 first example. Yields of dewaxed oil of 81.2, 81.9 and 83.0% by volume having pour points of -5° F., -5° F. and -10° F., respectively, were obtained when employing the 16, 24 and 26 hour air blown samples, respectively. The melting 30 points (Ubbelohde) of the separated waxes were 125, 127 and 125, respectively, and the filter rates were 8.1, 10.6 and 11.1 gal./sq. ft./hr., respectively.

Another portion of the above oxidized acid 35 treated S. A. E. 50 wax was added to an S. A. E. 50 waxy distillate in amount as to incorporate 0.5% by weight of the oxidized wax. The oil was dewaxed according to the propane dewaxing method described above employing, however, a 40 volumetric ratio of two volumes of propane to one of the oil. A yield of dewaxed oil of 84.0% by volume was obtained having a pour point of -15° F. The melting point (Ubbelohde) of the wax separated was 145° F. The filter rate was 45 5.8 gal./sq. ft./hr.

From the foregoing example compared with the example of dewaxing the S. A. E. 50 stock employing the S. A. E. 10 oxidized wax as a wax separation aid, it will be observed that better 50 yields and filter rates were obtained by using the oxidized S. A. E. 50 wax on the S. A. E. 50 waxy distillate. However, the S. A. E. 10 oxidized wax was more effective as a wax separation aid in dewaxing the S. A. E. 20 waxy distillate. This indicates that the nearer the oxidized wax 55 resembles the type of wax in the oil to be dewaxed, the better the yields and filter rates obtained.

In order to determine the effect of oil contained in this type of wax, i. e. wax separated from S. 60 A. E. 50 vacuum distillates, two acid treated waxes and containing, respectively, 59.6% and 11.6% of oil as determined by the acetone-benzene method were separately oxidized with pure oxygen. The oxidation on the two waxes was carried under 65 substantially identical conditions. Each wax was oxidized for 22 hours at a temperature of 450° F. The wax which contained 59.6% of oil had an acid number of 12.0 and a saponification number of 16.3 after oxidation, while the wax of low oil 70 content had an acid number of 15.2 and a saponification number of 85.1.

When S. A. E. 20 vacuum distillates were dewaxed with 1% of the above wax separation aids and according to the procedure set forth in the 75 first example, about 82.3% by volume of dewaxed

oil having a pour point of -5° F. was recovered when employing the oxidized wax which had the lower oil content. The wax separated from the oil had a melting point (Galician) of 129.5° F. The results obtained employing the oxidized wax 5 of higher oil content were not quite as remarkable, the yield of oil being 70.1% by volume of a 5° F. pour point and the melting point of the wax separated was only 119° F.

The above results indicate that it is desirable 10 to deoil the wax to at least a 40% oil content prior to oxidation with the oxidizing gas.

In another run the slack wax obtained from an S. A. E. 50 waxy distillate was deoiled by extraction with a mixture of 75% benzene and 25% acetone. The deoiled wax had a melting point (Ubbelohde) of 167° F. The wax was oxidized 15 in a stream of air and hydrogen peroxide for $8\frac{1}{4}$ hours at a temperature of 380 to 420° F. The finished modifier had an acid number of 95, a 20 saponification number of 238 and was quite light in color.

The potency of the above described modifier is evidenced by the fact that when the S. A. E. 20 25 vacuum distillate heretofore described was propane dewaxed, using 0.5% of the wax separation aid according to the procedure herein set forth, a yield of dewaxed oil of 86.9% by volume was obtained having a pour point of 0° F. The filter rate was 11.5 gal./sq. ft./hr. The wax recovered 30 had a melting point (Ubbelohde) of 128° F.

Examples of use of oxidized S. A. E. 20 wax

A slack wax recovered from an S. A. E. 20 waxy 35 distillate obtained by the vacuum distillation of a Santa Fe Springs crude oil by the propane dewaxing method employing asphalt as a filter aid was deoiled by the acetone-benzene method described above to an oil content of approximately 8.3%, after which it was acid treated and wet 40 neutralized. The treated wax had a melting point (A. S. T. M. method) of 138.3° F. The material was then oxidized with pure oxygen at a temperature of 450° F. for 22 hours. The finished product 45 had an acid number of 6.7 and a saponification number of 183.5.

Employing approximately 1% of this wax modifier as a dewaxing aid in the dewaxing of an S. A. E. 20 waxy distillate according to the propane dewaxing method described in the first example with the exception that a higher filter pressure of 50 to 100 lbs./sq. in. was employed, a 50 yield of 83.7% by volume of dewaxed oil having a pour point of -5° F. was obtained. The filter rate was 3.8 gal./sq. ft./hr. and the melting point (Galician) of the wax separated was 130° F.

In order to determine the effect of the oil content of oxidized S. A. E. 20 wax as a wax modifier, a mixture of 50% of the above described deoiled and acid treated wax obtained from the S. A. E. 20 waxy distillate and 50% of dewaxed S. A. E. 20 oil was oxidized with pure oxygen at 60 450° F. for 22 hours.

When employing 1% of the above oxidized mixture to dewax an S. A. E. 20 waxy distillate, it was observed that the yield was rather low, i. e. 65 70.6% by volume. The filter rate, however, was 4.2 gal. per sq. ft./hr. and the pour point of dewaxed oil was -10° F. The melting point (Galician) of the wax removed from the oil was 70 118° F. These figures would indicate that while the use of an oxidized S. A. E. 20 wax having a large amount of oil is not as good as a deoiled 75 oxidized wax, it has considerable properties as a

wax modifier. When employing oxidized wax modifiers of the S. A. E. 20 type, it is quite desirable to reduce the oil content to approximately 10-20% prior to oxidation.

5 In addition to the foregoing oxidized waxes as dewaxing aids, we have observed that oxidized petrolatum which is a wax recovered from wax containing residues and oxidized waxes obtained from S. A. E. 70 waxy oil distillates possess remarkable potency in the dewaxing of petroleum oils. These waxes may or may not be deoiled prior to oxidation to render them active as wax modifiers. However, it has been found that the lower the oil content of the wax, the more active 10 will be the wax as a dewaxing aid after oxidation.

15 We have also discovered that oxidized waxes of the natural type are also effective in improving the dewaxing characteristics of wax-containing oils. Wax separation aids of this type include oxidized montan wax, carnauba wax and beeswax.

20 We have also discovered that oxidized oils are also active in aiding dewaxing of petroleum wax containing fractions. An S. A. E. 70 dewaxed oil produced from a Pennsylvania type crude oil by blending bright stock and neutrals was partially 25 oxidized by being exposed to the atmosphere for three months to a nearly continuous temperature of 340° F. under conditions of considerable agitation. The oxidized oil had an acid number of 30 1.40 and a saponification number of 19.

25 A propane dewaxing run, employing 1% of the oxidized material with S. A. E. 20 vacuum distillate was carried out according to the propane dewaxing method described in the first example. 30 A yield of 79.6% by volume of dewaxed oil having a pour point of -5° F. was obtained. The filter rate was 7.3 gal./sq. ft./hr. The melting point (Galician) of the separated wax was 125° F.

35 While the above experiment was carried out 40 with an oil oxidized for a long period of time, it is obvious that the material may be duplicated or improved by oxidizing the bright stock for a short time under more drastic conditions of oxidation. Also, similar results may be obtained by employing 45 the oxidized petroleum fractions after solvent extraction with a selective solvent such as sulfur dioxide, phenol, nitrobenzol and the like.

50 In one case a 650 steam refined oil obtained from a Pennsylvania crude oil residuum from which wax was separated was oxidized for 22 hours at 450° F. with pure oxygen. The acid number of the oxidized oil was 5.3 and the saponification number was 73.0.

55 When 1% of the above oxidized material was employed as a wax separation aid in propane dewaxing an S. A. E. 20 vacuum distillate in accordance to the procedure outline under the first example, a yield of dewaxed oil was obtained of approximately 80.8% by volume having a pour 60 point of -10° F. The filter rate was 8.2 gal./sq. ft./hr. The melting point (Galician) of the wax separated was 128° F.

65 In another case, a Santa Fe Springs residual oil which was deasphalting by commingling the oil with 5 volumes of propane at 70° F. to precipitate the asphalt was oxidized after removal of propane with pure oxygen at a temperature of 450° F. for 22 hours. When employing 1% of this material as an aid in propane dewaxing an S. A. E. 70 vacuum distillate, excellent results were obtained with respect to yields of oil of desired pour point, filter rates and melting point of the separated wax.

75 We have also obtained improved filter rates by first oxidizing the wax containing oil to be de-

waxed, that is, instead of adding oxidized wax to the oil to be dewaxed, the latter is subjected to an oxidation reaction and is subsequently dewaxed by chilling and filtering. In one case, a wax containing lubricating distillate of S. A. E. 20 grade (from Santa Fe Springs crude) was air blown at a temperature of 300° F. for approximately 22 hours. The rate of air introduction was 6 liters per minute for a 7 liter charge, the air being first passed through a sulfuric acid trap to remove moisture contained in the air. The oil was then mixed at a temperature of 250° F. with liquid propane at a volumetric ratio of 8 volumes of propane to one of the oil. The mixture was then chilled to -35° F. by vaporizing propane under gradually reduced pressure until a pressure of 10 lbs. per square inch existed in the chilling vessel. The chilled mixture was then filtered under a pressure of less than 25 lbs. per square inch at -30° F. It was found that a filter rate of approximately 3.7 gal./sq. ft./hr. was obtained and a yield of dewaxed oil of 70.7% by volume having a pour point of 5° F. These figures indicate that by oxidizing the oil to be dewaxed superior results may be obtained over dewaxing oils without prior oxidation.

20 It will be observed that the foregoing description of our invention is not to be considered as limiting as many variations thereof may be made by those skilled in the art within the scope of 30 the following claims:

We claim:

1. In the art of dewaxing wax-containing oils involving the separation of wax from oil, the step of preparing the oil for the separation of wax therefrom comprising adding an oxidized wax to said wax-containing oil. 35

2. A process as in claim 1 in which the oxidized wax is produced by the oxidation of wax with a mixture of hydrogen peroxide in the presence of air. 40

3. A process according to claim 1 in which the oxidized wax is a wax which has been oxidized in the presence of a catalyst. 45

4. A process according to claim 1 in which the oxidized wax is a wax which has been oxidized in the presence of a catalyst selected from the class consisting of chlorides of iron, zinc, tin, aluminum and naphthenates, oleates, stearates, ricinoleates and palmitates of sodium, copper, magnesium, aluminum, cobalt and iron. 50

5. A process according to claim 1 in which the oxidized wax is a wax which has been oxidized in the presence of iron naphthenate. 55

6. A process for the separation of wax from wax-oil mixtures containing the same which comprises mixing said wax-oil mixture with an oxidized wax, chilling the mixture to separate wax and removing the wax from the chilled oil. 60

7. A process according to claim 6 in which the oxidized wax has a melting point higher than the unoxidized wax. 65

8. A process for the separation of wax from oils containing the same which comprises mixing said wax-containing oil with a paraffinic substance solid at room temperature which has been substantially freed from oil and oxidized, chilling the mixture to separate wax and removing wax from the chilled mixture. 70

9. A process for the separation of wax from oils containing the same which comprises mixing said wax-containing oil with a paraffinic substance solid at room temperature which has been substantially freed from oil and resinous ma- 75

terial and oxidized, chilling the mixture to separate wax and removing wax from the chilled mixture.

10. A process for the separation of wax from 5 oils containing the same which comprises mixing said wax-containing oil with a slack wax which has been oxidized, chilling the mixture to separate wax and removing wax from the chilled mixture.

10 11. A process according to claim 10 in which the oxidized wax has an acid number of less than approximately 5 and a saponification number of less than approximately 30.

12. A process for the separation of wax from 15 oils containing the same which comprises mixing said wax-containing oil with a slack wax which has been deoiled and oxidized, chilling the mixture to separate wax and removing wax from the chilled mixture.

20 13. A process according to claim 12 in which the oxidized wax has an acid number of less than 100 and a saponification number of less than 300.

14. A process for the separation of wax from 25 oils containing the same which comprises mixing said wax-containing oil with oxidized wax, said oxidized wax comprising a wax prior to oxidation having substantially the same characteristics as the wax contained in the oil desired 30 to be dewaxed, chilling the mixture to separate

wax and removing the wax from the chilled mixture.

15. A process for the separation of wax from 5 oils containing the same which comprises mixing oxidized wax with wax-containing oil, chilling said mixture to separate wax, removing the wax from the chilled mixture and employing said separated wax as charging stock for the production of oxidized wax to be used as a wax separation aid to the oil to be dewaxed having the 10 same characteristics as the oil from which said wax was separated.

16. A process for the separation of wax from 15 oil which comprises mixing said oil with a diluent and an oxidized wax, chilling the mixture to separate wax and removing the wax from the oil.

17. A process for the separation of wax from 20 wax-oil mixtures which comprises mixing the oil with an oxidized wax and with a liquefied normally gaseous hydrocarbon, chilling the diluted 25 wax-oil mixture containing the oxidized wax to a sufficiently low temperature to precipitate the oxidized wax and the wax contained in the wax-oil mixture and separating the precipitated wax and oxidized wax from the diluted oil.

18. A process according to claim 17 in which the liquefied normally gaseous hydrocarbon comprises liquid propane.
